UNITED STATES PATENT OFFICE.

JOHN M. BURR, OF NORWALK, CONNECTICUT.

WATER-CLOSET TANK MECHANISM.

SPECIFICATION forming part of Letters Patent No. 761,758, dated June 7, 1904.

Application filed July 18, 1903. Serial No. 166,152. (No model.)

To all whom it may concern:

Be it known that I, JOHN M. BURR, a citizen of the United States, residing at Norwalk, county of Fairfield, State of Connecticut, have 5 invented a new and useful Water-Closet Tank Mechanism, of which the following is a specification.

This invention is applicable to any of the various types of siphon, wash-down, and wash-10 out water-closets now in general use.

In plunger-valve water-closets as ordinarily constructed the flow of water from the tank through the flush-pipe ceases the instant the chain is released, and in all the types of water-15 closets having a continuous flow without holding the chain there is more or less suction of air into the flush-pipe, which makes the closets unpleasantly noisy, no matter how efficient they may be in other respects.

20 It is one of the objects of this invention to produce a water-closet having a ground-seat plunger-valve and mechanism operating in connection therewith which shall make the tank mechanism perfectly tight, thereby preventing waste of water, and perfectly noise-25 less, as suction of air in the flush-pipe is absolutely prevented—a mechanism, in brief, having all the advantages of the best siphon mechanisms now in use without any of the 30 disadvantages that are inherent in all water-closets that operate on the siphon principle.

A further object of the invention is to produce a water-closet tank mechanism having a "continuous" flow, so called, without a si-35 phon.

A further object of the invention is to produce a water-closet tank mechanism having an automatic overflow without the use of an over-flow-pipe.

40 A further object of the invention is to produce a water-closet tank mechanism in which the cost of construction shall be reduced to the minimum, which shall be without parts liable to wear out and need renewing, without 45 washers which quickly wear out and leak, and which shall have a plunger-valve with a seat that is in use self-grinding.

A further object of the invention is to produce a water-closet tank mechanism so con-50 structed that the valve will operate automati-

ically to stop the flow of water from the tank before the water in the tank is exhausted and before air can pass in.

With these and other objects in view the invention consists in certain constructions and 55 in certain parts, improvements, and combinations, which will be hereinafter described and then specifically pointed out in the claims hereunto appended.

In the accompanying drawings, forming 60 part of this specification, Figure 1 is a longitudinal section of a water-closet tank with my novel tank mechanism in side elevation, showing the water-level and the position of the parts when the tank is filled to the normal 65 height and the valve closed; Fig. 2, a plan view; Fig. 3, a longitudinal section showing the position of the parts after the valve has been raised and the water has commenced to flow into the flush-pipe, this view also show-70 ing a slightly-different mode of adjusting the cross-bar that controls the automatic overflow; Fig. 4, a transverse section on the line 4-4 in Fig. 3, but showing the overflow cross-bar adjusted as in Fig. 1; and Fig. 5 is a detail 75 sectional view on the line 5-5 in Fig. 3.

10 denotes a tank, which may be of the ordinary or any preferred construction. The supply-pipe is not shown, for the reason that my present mechanism relates solely to the 80 emptying of the tank, which may be filled in any ordinary or preferred manner.

11 denotes the flush-pipe, which is connected, by means of a suitable coupling, (indicated by 12,) with a downwardly and inwardly 85 tapering ground valve-seat 13, which opens into the tank.

14 denotes a plunger-valve, which is carried by a stem 15, extending upward through a frame 16, rigidly secured within the tank. 90 The upper end of the valve-stem is shown as connected, by means of a chain 17, with an operating-lever 18, which may be operated by means of a depending pull-chain (not shown) or in any ordinary or preferred manner. The 95 valve-stem is shown as provided with a longitudinal vent-hole 19, the purpose of which will presently be fully explained. The valve is provided with a cross-bar 20, the opposite ends of which are adapted to be engaged by notches 100

21 in the downwardly-extending arms 22 of a yoke 23, the opposite sides of which are pivoted to the frame, as clearly shown in Fig. 4. The special details of construction of the frame 5 are not of the essence of the invention. It is sufficient that the frame be made sufficiently rigid to support the operative parts of the mechanism. It will be noted in Fig. 1 that the shape of the yoke in side elevation is that 10 of a bell-crank lever.

24 denotes a rod extending from the center of the yoke, which carries a relatively small float 25, which may be of glass or copper.

26 denotes an arm extending from the frame, 15 to the upper end of which a yoke 27 is pivoted. A rod 28 extends from this yoke, which is shown as provided with a hub or ball 29, through which a threaded rod 30 passes. At the upper end of rod 30 is a relatively large 20 float 31, the height of this float being adjustable by means of the threaded rod, which passes through the hub and is locked in position after adjustment by a set-screw 32.

It will of course be obvious that the details 25 of construction may be greatly varied without departing from the principle of the invention. For example, it is not essential that yoke 27 and rod 28 be made in two parts or that the arrangement of yoke 23 be as shown 30 or that said yoke be provided with two downwardly-extending arms 22 instead of one. I preferably, however, construct the mechanism substantially as illustrated in the drawings and have not illustrated modifications, as 35 their construction is obvious.

33 denotes a cross-bar on the valve-stem, which is adapted to be engaged by yoke 27 to lift the valve-stem and the valve and permit water to pass into the flush-pipe should water 40 rise too high in the tank. This cross-bar is necessarily adjustable on the valve-stem.

In Figs. 1, 2, and 4 I have shown the valve-stem as provided with an external thread 34, and the cross-bar is provided with a threaded 45 hub 35, engaging it. To adjust the cross-bar in this form, the operator simply rotates the cross-bar and the hub upward or downward, as may be necessary, on the threaded valve-stem.

50 In Figs. 3 and 5 I have shown a form in which neither the valve-stem nor hub 34 are threaded; but the hub slides freely on the valve-stem and is locked at any required adjustment by a set-screw 36.

55 The operation is as follows: The water-level in the tank is determined by the supply mechanism, which, as already stated, forms no portion of my present invention. Having determined the height of the water-level, float 60 31 is adjusted to correspond therewith by turning the float and rod 30 upward or downward, as may be required, and locking it in place after adjustment by means of the set-screw. In use the usual movement of the operating-lever raises the valve-stem and valve,

and the water in the tank commences to flow out through the flush-pipe. It will of course be understood that as float 25 is normally covered by the water its tendency is to rise and that it holds downwardly-extending arms 70 22 pressed against cross-bar 20 on the valve. As soon as the valve-stem and valve are raised, therefore, float 25 will rise and will swing arm 22 inward, as in Fig. 3, and cause notches 21 in said arms to engage cross-bar 20 and lock 75 the valve at the raised position, in which position it will remain until cross-bar 20 is released by the fall of float 25. This release of the cross-bar and valve will take place as soon as the water in the tank has fallen to the pre-determined level—that is, far enough so that it will not hold said float 25 at the raised position, as in Fig. 3. As soon as the water in the tank fails to support the float it falls, which swings arms 22 outward, as in Fig. 1, 85 thereby disengaging the notches from cross-bar 20 and permitting the valve to fall by its own weight and instantly shut off the flow of water into the flush-pipe. It will be noted, therefore, that the tank is never emptied in 90 use, the parts being so proportioned and arranged as to shut off the flow of water into the flush-pipe before it has fallen low enough to permit any suction of air into the flush-pipe, thereby wholly preventing the noise ordinarily caused by suction.

The function of float 31 is solely to produce an automatic flow from the tank should the water therein rise above the normal level through any cause whatever. Under ordinary conditions yoke 27, rod 28, and float 31 rise and fall with the water in the tank, but without effect on the normal operation of the mechanism. It will be noted in Fig. 1 that cross-bar 33 is so adjusted on the valve-stem 100 as to be just above yoke 27 when the water in the tank is at its normal level. Should the water rise above this level, however, it will necessarily raise float 31, rod 28, and yoke 27, placing the latter in engagement with cross-bar 33 and raising the valve-stem and valve, which permits the water in the tank to pass out through the flush-pipe until the flow is again stopped through the operation of float 25 precisely the same as though the mechanism had been operated in the usual manner by means of the operating-lever. This automatic operation of float 31 will continue so long as water in the tank continues to rise above the normal level, thus making overflow 110 of the tank impossible.

The function of the longitudinal vent-hole 19 in the valve-stem is to permit the flush-pipe to slowly empty itself after the flow of water from the tank has been cut off. This 125 vent-hole is provided for the reason that no air can enter the flush-pipe with the water from the tank, so that when the valve is released through the operation of float 25 a solid column of water remains in the flush- 130

pipe. By providing a vent-hole through the valve-stem and of course through the valve sufficient air is permitted to enter the flush-pipe to cause the water therein to run out.

5 Having thus described my invention, I claim—

1. In a mechanism of the character described the combination with a valve-seat, a plunger-valve, a stem therefor and a cross-bar on the 10 valve-stem, of float-controlled means to engage said cross-bar for locking the valve at the raised position and for releasing the valve when the water in the tank has fallen to a predetermined level, a float 31 and an arm by 15 which said float is carried and which is adapted to engage the cross-bar to lift the valve-stem and valve should water in the tank rise above a predetermined level.

2. In a mechanism of the character described 20 the combination with a tapering valve-seat and a correspondingly-tapering plunger-valve, of means for lifting the valve from the seat, a float 25 and connections for automatically locking the valve at the raised position and 25 for releasing the valve so that it will close automatically when the water has fallen to a predetermined level and a float 31 and con-

nctions whereby the valve is raised should the water rise above a predetermined level.

3. In a mechanism of the character described 30 the combination with a downwardly and inwardly tapering valve-seat and a correspondingly-tapering plunger-valve, of a float 25 and connections for positively locking the valve at the raised position and for releasing it when 35 the water has fallen to a predetermined level and a float 31 and connections for automatically lifting the valve should the water rise above the normal level.

4. In a mechanism of the character de- 40 scribed, the combination with a valve-seat and a valve therefor, of a screw-threaded valve-stem, a cross-bar having a threaded hub engaging said threaded valve-stem, and vertically adjustable thereupon, and a lever having 45 a float, said lever being adapted to engage the cross-bar to raise the valve should the water rise above the normal level.

In testimony whereof I affix my signature in presence of two witnesses.

JOHN M. BURR.
